(57) **CLAIM**

The ornamental design for an axle anti-sway unit for a vehicle, as shown and described.

DESCRIPTION

FIG. 1 is a first side elevational view of an axle anti-sway unit for a vehicle showing my new design.

FIG. 2 is a second side elevational view of the axle anti-sway unit for a vehicle.

FIG. 3 is an end elevational view of the axle anti-sway unit for a vehicle.

FIG. 4 is a top/bottom plan view of the axle anti-sway unit for a vehicle; and,

FIG. 5 is a first side elevational view of the axle anti-sway unit for a vehicle shown in use.

The connecting rods are shown broken away for ease of disclosure.

The broken lines in the drawings represent environmental structure only and form no part of the claimed design.
